UNITED STATES PATENT OFFICE.

RICHARD G. McCANN AND PAUL J. HUETTER, OF SPOKANE, WASHINGTON.

ASSEMBLING TOOL.

Application filed February 16, 1926. Serial No. 88,534.

Our invention relates to an improved assembling tool of the pliers type especially adapted for the purpose of applying piston rings to and removing them from their 5 grooved pistons.

The manually operated tool is provided with means for distending or separating the ends of the standard type of resilient, split, piston ring, combined with means for supporting or carrying the ring in distended position, either for placing the ring in position on the piston, or for removing the ring from the piston. The tool is also provided with means, adjustable to various sizes of 10 piston rings, for limiting the distending action of the tool to prevent excessive expansion of the piston ring that might result in injury to the ring.

Our invention consists in certain novel 20 combinations and arrangement of parts whereby a hand tool of this character is provided that is simple in construction and composed of a minimum number of parts, thus rendering it comparatively inexpensive 25 in the cost of manufacture; which may be manipulated with facility by the use of one hand; and which is reliable in the performance of its required functions.

In the accompanying drawings we have 30 illustrated one complete example of the physical embodiment of our invention wherein the parts are combined and arranged in accordance with the best mode we have thus far devised for the practical application of the principles of our invention.

Fig. 1 is a plan view of the device embodying our invention;

Fig. 2 is an edge view of the tool;

Fig. 3 is an enlarged detail plan view, 40 with the handles omitted for convenience of illustration, showing the tool applied to a piston ring and holding its ends open; and

Fig. 4 is an enlarged detail view showing 45 the relation of one of the supporting heads of the tool to the piston ring.

In order that the general assembly and relation of parts may readily be understood we have shown in Fig. 3 the overlapping ends 1 and 2 of a resilient split piston ring having shoulders 3, with the ends 50 sprung apart by the action of the tool, either for slipping the ring over the piston head to position for use, or for withdrawing the ring from its annular seat or groove in the piston preparatory to removal of the ring.

The tool is fashioned with a pair of

handles 4 and 5 normally held apart by a pair of spreader springs 6 having their outer ends secured to the inner faces of the handles, and their inner ends in frictional contact to normally hold the jaws 7 and 8 of the tool in closed position. The jaws overlap and are preferably formed integral with the complementary handles, and these flattened jaws are pivoted together at 9 so 60 that they may be opened by compressing the handles against their springs 6. The compressing movement of the handles, and consequently the opening movement of the jaws, is limited by an adjustable screw 10 65 which is threaded in a lug 11 of one of the jaws and is adapted to bear against a complementary lug 12 or abutment on the other jaw. In Fig. 3 it will be seen that the screw may be adjusted to cause contact of 70 its end with the abutment 12, and thus limit the closing movement of the handles and the opening movement of the jaws. In this manner excessive opening of the split resilient ring is prevented, it being understood 75 that excessive opening of the ring will result in distortion and consequent injury to the ring. By properly adjusting the screw 10 the opening movement of the ring may be predetermined and the danger of 80 ruining the piston ring is eliminated.

Each of the jaws is provided with a tapered and pointed spreader arm as 13 and 14 having outturned points 15, and these arms which are integral with the respective pivoted jaws, of course, swing outwardly or 90 inwardly on the pivot when the handles 4 and 5 are compressed and extended.

As seen in Fig. 3 the oppositely extending 95 points 15 of the tapered arms are designed to be slipped between the adjoining shoulders 3 of the overlapping ends 1 and 2 of the split resilient piston ring. The points, when inserted between the shoulders, provide an initial separating movement of the 100 ring-ends and then by compressing the handles of the tool the ends of the ring are separated the necessary distance to permit application of the ring to the piston or to permit removal of the ring from the piston 105 in well-known manner.

In co-action with the spreader jaws we provide means for supporting or carrying the ring in order that it may be manipulated with facility when being applied to 110 or taken from the piston. For this purpose we utilize a pair of spring-pressed carrier

bars 16 and 17, one located at the outer edge of each of the spreader arms, and supported in slide bearings 18 preferably formed integral with the arms. At their rear ends these bars are fashioned with bent or unhooked retaining ends 19 which project into slots 20 of the tapered spreader arms to limit the movement of the bars and prevent their displacement with relation to the arms.

At their outer ends these carrier bars are fashioned with carrier heads 21 formed with an approximate V-shape and bent at substantially right angles to the carrier bars.

As best seen in Fig. 4 these V-shaped heads are designed to impinge against the outer faces of the ring-ends 1 and 2, one at each side of the spreader arms, and a spring 22 coiled about the bar and interposed between the carrier head and a bearing lug 18, holds the carrier head in contact with the ring end.

Due to the V-shape of the carrier head and the tension of the spring of each carrier bar, these heads co-operate with the spreader points 15 of the spreader arms in holding the ring in the tool. Thus the split resilient ring may be held in one hand and the tool in the other hand. The tool is then applied to the ring, the outwardly turned points 15 being used to separate the shoulders of the ring, after which these points are forced into frictional contact with and between adjoining shoulders of the overlapping ends of the ring. The carrier heads 21 which impinge against the outer faces of the ring-ends are held in that position by the springs 22, and as the tension of these springs is not sufficient to overcome the

friction between the respective spreader 40 points and the ring-shoulders, it will be apparent that the ring will be held by the tool and may be manipulated freely for application to the piston or withdrawal therefrom.

After the ring has been seated in its groove in the piston, the tool may readily be detached therefrom by a slight pull to withdraw the spreader points from between the shoulders of the ring.

Having thus fully described our invention, what we claim as new and desire to secure by Letters Patent is—

1. The combination in a tool comprising a pair of pivoted jaws and spreader arms 55 thereon, of a spring-pressed carrier bar supported on each arm, and a frictional bearing head on each bar for co-action with the spreader arms in supporting a split ring.

2. The combination with a pair of pivoted jaws having arms and spreader points on said arms for engagement with the ends of a split ring, of a pair of spring-pressed carrier bars supported on said arms, and a V-shaped bearing head on each bar for frictional engagement with the split ring.

3. The combination in a tool of the pliers type with a pair of arms having oppositely extending spreader points, of an adjustable screw and abutment-lug for limiting the 70 spread of the arms, a spring-pressed carrier bar supported on each arm, and a V-shaped bearing head on each bar for frictional engagement with a piston ring.

In testimony whereof we affix our signatures.

RICHARD G. McCANN.
PAUL J. HUETTER.
